STERILIZING AND WARMING DEVICE FOR
CONTAINERS

Wesley P. Clements, Detroit, Mich.

Application August 31, 1936, Serial No. 98,831
In Canada May 30, 1936

2 Claims. (Cl. 21—79)

This invention relates to improvements in sterilizing and warming devices for containers, and is primarily intended for sterilizing and warming infants' feeding bottles and nipples, and keeping filled bottles warm.

It is an object of the invention to provide a sterilizing device wherein bottles and other containers and nipples may be thoroughly sterilized both inside and out, and wherein the interiors of the articles sterilized are also thoroughly washed with boiling water.

Another object of the invention is to provide a sterilizing and warming device wherein a tray is provided to support the articles to be warmed or sterilized; wherein removable tubes are arranged to extend into inverted containers resting upon the tray to be sterilized; and wherein filled containers may be placed upright upon the tray for warming their contents after the tubes have been removed.

A further object of the invention is to provide such a sterilizing and warming device wherein the tray and its contents are readily removable.

Yet another object of the invention is to provide a sterilizing device wherein the upper extremities of the tubes are provided with means for retaining the articles placed over them spaced from the said extremities to insure a free flow of boiling water from the tubes.

Having thus briefly and broadly stated some of the major objects and advantages of the invention I will now describe the invention in detail with the aid of the accompanying drawing, in which:

Figure 1 is a vertical sectional view of the invention with the cover in position, and inverted bottles and a nipple arranged over the tubes for sterilization.

Figure 2 is another vertical section showing the tubes removed and filled bottles resting upon the tray for warming.

Figure 3 is a perspective view of the tray and its base removed from the pan, and

Figure 4 is an enlarged sectional view showing a nipple mounted for sterilizing upon one of the tubes.

Referring to the drawing, 1 designates a pan or container having a conventional enclosing wall 2, and 3 indicates a lid or cover having a depending annular flange 4 which rests against the said wall 2.

Removable within the pan 1 is a warming and sterilizing unit 5. The latter consists of a base 6 the periphery of which rests upon the bottom of the pan. The base is provided with an annular

raised portion 7 concave on its underside to permit water to circulate freely beneath it, and the central portion 8 of the base is spaced only slightly above the bottom of the pan. Extending upwardly through the raised portion 7, and preferably through the highest portion thereof, are ferrules 9. Through the base 6 suitable means are provided, such as the opening 10, to permit water to pass through it to the underside. Moreover this opening is generally provided through the central portion 8 for a reason hereinafter made clear.

Extending upwardly from the base 6 is a central upright 11, the upper extremity of which may terminate in a handle as shown at 11a, and a plurality of side uprights 12. Supported by the latter above the top of the base 6 is an annular tray 13, and spaced above the latter are a plurality of arms 14 which extend from the upright 11 to each of the uprights 12. These arms act as supports for bottles or other articles resting upon the tray and prevent them falling over particularly when the unit is being inserted into or removed from the pan. 15 denotes tubes which are readily insertable into the ferrules 9 and which are prevented from entering the latter more than a predetermined distance by beads 15a. Springs 16 are mounted in the upper extremities of the tubes 15 and are provided with enlarged upper extremities which remain outside the said tubes.

When bottles or nipples or other articles are to be sterilized the tubes 15 are arranged in the ferrules 9 and upon the tray 13 the bottles A and AA are placed in inverted position as shown in Figure 1. Water is placed in the pan 1 to a level somewhat below the tray 13, and the pan is placed over a stove or other heating medium.

When the water boils it passes up through the tubes 15 and thoroughly washes and sterilizes the inside of the bottles or other articles placed thereover. Due to the narrow spacing between the central portion 8 of the base 6 and the bottom of the pan 1 water therein boils furiously and is expelled through the tubes 15 when the upper surface of the water is barely agitated. Consequently it is preferable to provide a free water inlet from above the base 6 through an opening located as shown at 10, because in this manner thorough washing and sterilizing of the bottle interiors occurs while only a relatively small amount of steam, sufficient however to sterilize the outsides of the bottles, is generated, and without necessitating boiling the water so fast that

an appreciable amount of steam pressure is built up within the vessel. The lid 3 is suitably apertured at 3a to permit the escape of steam if for any cause the device is left too long over too fierce a fire. The lid 3 is also provided with a handle 3b.

In Figure 1 it will be noted that two bottles A and AA of different lengths and contours are arranged over the tubes 15. The shorter bottle A 10 is prevented from resting upon the upper extremity of its tube by one of the springs 16. In that manner a free flow of water from the tube into the bottle for washing and sterilizing it is assured irrespective of the height of the bottle. Again 15 the springs 16 are so formed that they will support the smaller outer portion BB of a nipple B, thereby insuring a free circulation of water into the nipple and particularly through its portion BB through which the infant's food passes.

20 When the device is used for warming filled bottles, the tubes 15 are removed from their ferrules 9 and the pan is filled with hot water to any desired depth.

While in the foregoing the preferred embodiment of the invention has been described and shown, it is understood that the construction is susceptible to such alterations and modifications as fall within the scope of the appended claims.

What I claim as my invention and desire to 30 secure by Letters Patent is:

1. A combination bottle sterilizer and warmer comprising a container, a base removably supported on the container and having its margin resting upon the container bottom, the remainder 35 of the base being spaced above said bottom and being apertured for the passage of fluid into the

space between the base and the container bottom, an open tray designed to support a bottle in upright or inverted position supported by and over the base at a point substantially below the top of said container, a guide supported by said base above said tray for guiding the bottle to the tray and holding it in vertical position, a ferrule extending upwardly from the base providing fluid passage from the under side thereof, said ferrule being in vertical alignment with an open portion 10 of said tray, and a tube removably associated with said ferrule extending through the open portion of said tray.

2. A combination bottle sterilizer and warmer comprising a container, a base removably supported on the container and having its margin resting upon the container bottom, the remainder 15 of the base being spaced above said bottom and being apertured for the passage of fluid into the space between the base and the container bottom, an open tray designed to support a bottle in upright or inverted position supported by and over the base at a point substantially below the top of 20 said container, a guide supported by said base above said tray for guiding the bottle to the tray and holding it in vertical position, a ferrule extending upwardly from the base providing fluid 25 passage from the under side thereof, said ferrule being in vertical alignment with an open portion of said tray, a tube removably associated with said ferrule extending through the open portion of 30 said tray, and a removable cover for said container apertured to permit the passage of steam therethrough.
